UNITED STATES PATENT OFFICE

134,038

DESIGN FOR A DISPENSER

Charles R. Bennett, Cleveland, Ohio

Application July 21, 1941, Serial No. 102,328

Term of patent 7 years

To all whom it may concern:

Be it known that I, Charles R. Bennett, a citizen of the United States and a resident of Cleveland, Cuyahoga County, and State of Ohio, have invented a new, original, and ornamental Design for a Dispenser, of which the following is a specification, reference being had to the accompanying drawings, forming a part thereof.

Figure 1 is a side elevational view of a dispenser showing my design, it being understood that the opposite side is substantially similar to the side illustrated;

Figure 2 is a front elevational view; and

Figure 3 is a bottom plan view thereof, reduced in scale.

The shading of the bracket and bottom portions of the dispenser indicates that these parts are of gray or silver color, such as chrome plate.

I claim:

The ornamental design for a dispenser, as shown and described.

CHARLES R. BENNETT.
